ABSTRACT: A winding for electrical inductive apparatus having a plurality of pancake coils, each of which have a plurality of turns provided by radially interleaved conductors. The first and second pancake coils adjacent the line end, or ends, of the winding, are interconnected to provide an interleaved turn, high series capacitance arrangement wherein the electrical circuit spirals inwardly in the first pancake coil and outwardly in the second. The third and fourth pancake coils are also interconnected to provide an interleaved turn, high series capacitance arrangement, but the sequence is reversed to direct the electrical circuit outwardly in the third pancake coil and inwardly in the fourth to reduce the electrical stress between the inner turns of the second and third pancake coils.

FIG. 4.

FIG. 6.

ELECTRICAL WINDING

BACKGROUND OF THE INVENTION

1. Field of the Invention

The invention relates in general to electrical inductive apparatus, such as transformers, and more specifically to windings for electrical power transformers of the core-form type, which utilize a plurality of pancake coils disposed in spaced, side-by-side relation, and connected to increase the through or series capacitance of the winding.

2. Description of the Prior Art

My copending application Ser. No. 686,912, filed Nov. 30, 1967, now Pat. No. 3,477,052 which is assigned to the same assignee as the present application, discloses a new and improved high series capacitance interleaving arrangement for the high voltage winding of power transformers of the core-form type, which is broadly of the twin interleaved type since the basic pattern requires the interconnecting of two adjacent pancake coils. Each pancake coil has a plurality of conductor turns provided by first and second conductors wound together to provide first and second radially interleaved coil sections, with the electrical circuit spiraling through predetermined radial sections of the first and second coils of a pair, and then returning to the first coil of the pair to traverse the remaining coil sections of the pair. The art prior to my copending application taught the exchanging of coil sections each time the electrical circuit proceeds from the first to the second pancake coils of the pair, while my copending application teaches reducing the magnitude of voltage oscillations, and hastening their decay, by making each pass of the circuit through the coils of a basic pair via like coil sections. This arrangement substantially reduces stress build up at the midpoint of adjacent coil builds. However, high electrical stresses are experienced between the inner turns of the second and third pancake coils from the line end of the winding, or ends, when using a twin interleaved winding arrangement, which makes it mandatory that increased insulation be disposed in this area at the sacrifice of size and space. Thus, it would be desirable to reduce the electrical stress at this location, in order to either reduce the insulating clearances necessary at this location, or to provide a greater factor of safety.

SUMMARY OF THE INVENTION

Briefly, the present invention is a new and improved twin interleaved winding for electrical inductive apparatus, including a plurality of pancake coils arranged in a stack. Each pancake coil has first and second conductors wound together to provide first and second radially interleaved coil sections, respectively, and the first two pancake coils are connected in the twin interleaved arrangement disclosed in my copending application, wherein the circuit proceeds through the first and second pancake coils via like coil sections on each of the first and second passes through these coils, with the interconnections between the like coil sections of the two coils being made between the innermost turns of the coil sections. The third and fourth pancake coils are also twin interleaved, with the circuit proceeding through the third and fourth pancake coils via like coil sections on each pass through the coils, but in this instance the interconnections between the like coil sections of the two coils are made between the outermost turns of the coil sections. This arrangement reduces the voltage between the innermost turns of the second and third pancake coils of the winding to one-half the voltage across one of the pancake coils.

BRIEF DESCRIPTION OF THE DRAWINGS

Further advantages and uses of the invention will become more apparent when considered in view of the following detailed description and drawings, in which:

FIG. 1 is a partial sectional elevational view of a magnetic core and high voltage winding assembly of a transformer constructed according to the teachings of the prior art;

FIG. 2 is a schematic diagram of the high voltage winding shown in FIG. 1;

FIG. 3 is a vector diagram which illustrates the electrical stresses between the innermost turns of the second and third pancake coils of the high voltage winding shown in FIG. 1;

FIG. 4 is a diagrammatic view of a twin interleaved high voltage winding constructed according to the teachings of the invention;

FIG. 5 is a schematic diagram of the high voltage winding shown in FIG. 4; and

FIG. 6 is a vector diagram which illustrates the electrical stresses between the innermost turns of the second and third pancake coils of the high voltage winding shown in FIG. 4.

DESCRIPTION OF PREFERRED EMBODIMENTS

15 Referring now to the drawings, and FIG. 1 in particular, there is shown a partial sectional elevation of a transformer 10, constructed according to the teachings of the prior art. Transformer 10 is a power transformer of the core-form type, which may be single or polyphase. Since each phase of a 20 polyphase transformer would be similar, only one phase is shown in FIG. 1 in order to simplify the drawing.

Transformer 10 includes a magnetic core structure 12, which may be of conventional construction, including a winding leg 14 having an axis 20 about which high and low voltage 25 winding assemblies 16 and 18, respectively, are concentrically disposed. Low voltage winding assembly 18, which may be of conventional construction, has a plurality of conductor turns 22 insulated from the magnetic core 12 and the high voltage winding assembly 16 by electrical insulating means 24.

30 High voltage winding 16 includes a plurality of pancake or disc type coils 26, 28, 30 and 32, which are spaced axially apart in a stacked arrangement about the axis 20 of the magnetic core leg 14. Only four pancake coils, each having eight turns, are shown in FIG. 1, and in the remaining figures, in 35 order to adequately illustrate the prior art, and the teachings of the invention. It is to be understood that the winding may have any desired number of pairs of pancake coils, and turns per pancake coil, as required by a specific application.

The plurality of pancake coils of winding 16 are constructed 40 and connected to provide a high series capacitance winding, having a single series circuit between the line terminal 34 at the start of the winding 16, and a terminal at the finish end of the winding (not shown) which may be a line terminal or a neutral terminal, depending upon the specific construction and application of the transformer 10.

Each of the pancake coils 26, 28, 30 and 32 have a plurality 50 of conductor turns formed of at least first and second electrical conductors or strands spirally wound together about a common axis 20, to provide first and second coil sections I and II, respectively, each having inner and outer ends, the turns of which are radially interleaved with one another in substantially the same plane. The conductor turns are insulated from one another in a manner well-known in the art, with the insulation not being shown in order to clarify the drawings. Coil sections I and II are best illustrated in the schematic diagram of the high voltage winding 16, shown in FIG. 2. The two interleaved coil sections I and II of each pancake coil are shown slightly offset from one another in the schematic diagram of 55 FIG. 2, in order to more clearly denote the different radial locations of the first and second coil sections. In other words, the innermost turn of the pancake coil is in the first coil section I, and the second coil section II has the next to the innermost turn.

60 The pancake coils of high voltage winding 16 are connected to form a plurality of basic pairs, each having first and second adjacent pancake coils, to provide the basic interleaving arrangement. Then, the basic pairs are interconnected, in order to provide a single series circuit between the start and finish 65 ends of the winding. Since two pancake coils are required to complete the basic interleaving pattern, it is commonly referred to as twin interleaving. Twin interleaving, according to the teachings of the prior art, is performed by connecting the inner ends of unlike radial coil sections together in the first 70 and second pancake coils of each basic pair, and by connect-

ing the outer ends of like coil sections in the first and second pancake coils of each basic pair. More specifically, taking pancake coils 26 and 28 as the first and second pancake coils of a basic interleaved pair, respectively, the circuit enters the outer end of section II of the first pancake coil 26 via conductor 40, which is connected to line terminal 34, and it spirals inwardly via every other turn of the pancake coil. Each of the turns are identified with the letter C and a number which indicates the position of the turn relative to the line terminal 34. After reaching the innermost turn of the second coil section of pancake coil 26, the circuit proceeds to the end of the innermost turn of the first coil section I of the second pancake coil 28, via start-start connection 42, and spirals outwardly via every other turn until reaching the outer end of coil section I. The circuit then goes back to the first pancake coil 26, with the outer end of the first coil section of pancake coil 28 being connected to the outer end of the first coil section of pancake coil 26, via finish-finish connection 44, and the circuit again spirals inwardly via every other turn through pancake coil 26 until reaching the innermost turn of this section. The circuit again proceeds to the second pancake coil 28, with the end of the innermost turn of the first coil section of pancake coil 26 being connected to the end of the innermost turn of the second coil section of pancake coil 28, via start-start connection 46, and the circuit spirals outwardly through pancake coil 28 via every other turn, finally leaving pancake coil 28 via conductor 48, which is connected to the end of the outermost turn of the second coil section of pancake coil 28. This basic twin interleaved arrangement is then repeated for the next basic pairs of pancake coils, such as the second basic pair which comprises pancake coils 30 and 32, with conductor 48 entering the end of the outermost turn of coil section II of pancake coil 30.

Since each conductor turn has a number which identifies its position relative to the line terminal 34, the number of turns between predetermined locations of the winding may be readily ascertained. It will be noted that the difference in the number of turns between the innermost turns of pancake coils 28 and 30, which has been shown by experience to be a "weak" location in the winding from the standpoint of possible electrical breakdown, is 24 turns. Since there are 8 turns per pancake coil, the difference may be generalized as being $3N$, where N is equal to the number of turns in one pancake coil.

It should be noted that in the basic twin interleaved winding arrangement, that the series circuit spirals inwardly in the first pancake coil of the basic pair, and it spirals outwardly in the second pancake coil of the basic pair. Thus, the two pancake coils of each pair are "wound" in opposite circumferential directions, in order to obtain a uniform direction of instantaneous current flow in the pancake coils of the winding. In practice, this may be achieved by winding all the pancake coils in the same circumferential direction, and then breaking down and rewinding by hand alternate coils, in order to achieve the desired result without severing the conductor. Arrows 50 and 52 in FIG. 2 indicate that the series circuit in alternate pancake coils 26 and 30 spirals inwardly, and the arrows 54 and 56 indicate that the series circuit in the remaining pancake coils 28 and 32 spirals outwardly.

FIG. 3 is a vector diagram drawn with respect to the second and third pancake coils 28 and 30, which illustrates why the location between the inner turns of these pancake coils is an area of high electrical stress, which may fail during impulse or transient voltages, if special precautions are not taken to increase the insulating clearances at this location. The stress between the innermost turns of pancake coils 28 and 30 is equal to $3N$ or three times the voltage across one pancake coil, and this stress is indicated by vector 60. The stress between the high and low voltage windings 16 and 18 is indicated by the vector 62, which is substantially orthogonal to the direction of the stress between the two pancake coils. The stress between the innermost turns of the pancake coils adds vectorially to the stress between the high and low voltage windings, with the resulting stress being indicated by vector

64. If the insulating clearance in this location between the second and third pancake coils is not great enough, this resultant stress during surge testing or during a steep wavefront surge initiated by lightning or switching, may cause

5 a failure of the insulation at this location, such as a winding tube, establishing a creep path along the surface of the winding tube to ground. This location is especially critical in transformers with high BIL ratings, such as those of 1050 KV and above.

10 The stress between the innermost turns of pancake coils 28 and 30 may be reduced in the basic twin interleaving arrangement of FIG. 1 by first entering the outer end of the first coil section I of the first pancake coil, instead of the outer end of the second coil section II, as illustrated, which reduces the

15 stress between the innermost turns to $1N$ i.e., the voltage across one pancake coil, but this arrangement merely transfers the stress of three times the voltage across one pancake coil ($3N$) to the next to the innermost turns, which is therefore of little benefit.

20 Another modification of the basic interleaving arrangement shown in FIG. 1 is to first enter the outer end of the second coil section II of the first pancake coil in alternate pairs of coils, and in the remaining pairs the circuit is first directed into

25 the outer end of the first coil section I of the first pancake coil of a basic pair, which reduces the stress between the innermost turns to $2N$, or twice the voltage across one pancake coil, and the stress between the next to the innermost turns is also equal to $2N$.

30 My copending application, which changes the basic twin interleaved arrangement shown in FIG. 1 by directing each pass of the series circuit through two coils of a pair through like coil sections, to solve a different problem, i.e., the oscillatory voltage buildup which maximizes near the midpoint of the coil

35 builds, reduces the voltage stress between the innermost turns and between the next to the innermost turns to $2N$, regardless of whether the circuit first enters the first or the second coil sections of a basic pair, as long as the circuit enters the same coil section of each basic pair. If the circuit alternates its entry

40 into the coil sections of the first pancake coil of the basic pair, the voltage stress between the innermost turns, and between the next to the innermost turns, of the second and third pancake coils in the winding are $1N$ and $3N$, respectively, when the circuit first enters the end of the second coil section II of the first pancake coil of the basic pair, and $3N$ and $1N$, respectively, when the circuit first enters the outer end of the first coil section I of the first pancake coil of the basic pair.

45 In all of these arrangements, the sum of the voltage stress between the innermost turns and the voltage stress between the next to the innermost turns, is four times the voltage across one pancake coil, or $4N$. It would be desirable to reduce the voltage stress between the innermost turns to less than the voltage across one pancake coil, and to also reduce the sum of the voltage stress between the innermost turns, and between the next to the innermost turns, to less than $4N$.

50 FIG. 4 is a diagrammatic view of a high voltage winding 70, which is symmetrical about centerline 72, which may be used to replace the high voltage winding 16 shown in the transformer 10 of FIG. 1, to substantially reduce the voltage stress between the innermost turns of the second and third pancake coils from the line end, or ends of the winding.

55 More specifically, high voltage winding 70 includes a plurality of pancake coils, of which four are shown, referenced 65 74, 76, 78 and 80, with each having 8 conductor turns. Any desired number of pairs of pancake coils having any desired number of turns may be used, but only four pancake coils, or two pairs, are necessary to illustrate the teachings of the invention. Each of the pancake coils has a plurality of conductor turns formed of first and second conductors wound together to provide first and second radially interleaved coil sections, respectively, each having inner and outer ends, with the innermost turn of a pancake coil being in the first coil section, and the next to the innermost turn being in the second coil section.

70 75 FIG. 5 is a schematic diagram of high voltage winding 70, with

the first and second coil sections being offset slightly to indicate that the innermost turn is in coil section I.

The series circuit first enters the outer end of the second coil section of pancake coil 74 via conductor 82, which is connected to line terminal 84, and the circuit spirals inwardly, appearing at every other turn, referenced with the letter T and a number which indicates the location of the turn with respect to the line terminal 84. At the inner end of the second coil section II, which turn is referenced T4, the circuit proceeds to the inner end of the second coil section II of the next adjacent pancake coil 76, with a start-start connection 86. This turn of pancake coil 76 is also referenced T4, as the ends of these turns are at substantially the same potential. The circuit then spirals outwardly, appearing at every other turn in pancake coil 76, and it proceeds back to the first pancake coil 74 of the pair, with a finish-finish connection 88 which interconnects the end of the outermost turn of the second coil section of pancake coil 76 with the end of the outermost turn of the first coil section I of pancake coil 74. The series circuit then spirals inwardly through pancake coil 74 again, appearing at every other turn, until reaching the end of the innermost turn of the first coil section I. The circuit then enters the first coil section I of pancake coil 76 via conductor 90, and again spirals outwardly, appearing at every other turn until reaching the end of the first coil section I at turn T16. It will be noted that the series circuit to the first and second pancake coils 74 and 76 proceeds through the second coil sections of the pancake coils, and then through the first coil sections of the pancake coils, which arrangement reduces the magnitude of transient voltage oscillations produced by a surge potential, as taught by my copending application. It will also be noted, as indicated by arrows 92 and 94 in FIG. 5, that the series circuit spirals inwardly in the first pancake coil of the basic pair, and outwardly in the second pancake coil of the basic pair. Thus, these two coils are wound in opposite circumferential directions to produce an additive magnetomotive force in the associated magnetic core.

Instead of connecting the outer end of the first coil section of pancake coil 76 to the outer end of a coil section in the third pancake coil 78, as taught by the prior art, the outer end of the first coil section I of pancake coil 76 is connected to the inner end of the first coil section I of pancake coil 78, via finish-start connection 96. The series circuit spirals outwardly in pancake coil 78, appearing at every other turn until reaching the end of turn T20, where it proceeds via finish-finish connection 98 to the end of the outer turn of the first coil section I of pancake coil 80. The circuit spirals inwardly through pancake coil 80, appearing at every other turn until reaching the end of the innermost turn of the first coil section, and then it proceeds to the end of the innermost turn of the second coil section of pancake coil 78 via start-start connection 100. The series circuit again spirals outwardly through pancake coil 78, until reaching the end of the second coil section, where it proceeds via finish-finish connection 102 to the end of the second coil section in pancake coil 80. The circuit spirals inwardly through pancake coil 80 until reaching the end of the innermost turn of the second coil section at turn T32, and then leaves pancake coil 80 via connection 104. Thus, the second basic pair of pancake coils is "turned inside out" from its normal connection, with the forward proceeding intercoil connections 98 and 102 being disposed between the outermost turns of like coil sections, instead of between the innermost turns of the coil sections, and the reverse connection is made between the innermost turns of predetermined coil sections instead of between the outermost turns. Thus, instead of the series circuit spiraling inwardly in pancake coil 78 and outwardly in pancake coil 80, this normal sequence is reversed to direct the circuit outwardly in pancake coil 78, as indicated by arrow 108. In the first four pancake coils, the series circuit spirals inwardly in the first and fourth pancake coils, and outwardly in the second and third pancake coils.

Even though the pancake coils 78 and 80 are, in effect, turned inside out from their normal construction, the series

circuit still progresses through like coil sections in each pancake coil of the basic pair, to preserve the attenuation of transient voltages which such an arrangement provides.

The new and improved construction shown in FIG. 4 reduces the voltage stress between the innermost turns to one-half the voltage across one pancake coil, or $N/2$, while the voltage stress between the next to the innermost turn is $2.5N$, which makes the sum of the stresses between the innermost turns, and the stresses between the next to the innermost turns, equal to $3N$. This is a substantial reduction, compared to the prior art arrangements, with the stress between the innermost turn being only one-half the voltage across one pancake coil, compared to $1N$, the lowest stress between the innermost turns available with the prior art arrangements, and the sum of the stresses between the innermost turns, and the next to the innermost turns, is only $3N$, compared with $4N$ in the prior art. The advantage of such a reduction is shown in the vector diagram of FIG. 4, with vector 110 indicating the stress between the innermost turns, vector 112, which is orthogonal to vector 110, indicates the high-low stress between the high and low voltage windings, and vector 114 indicates the resultant stress. While the resultant stress 114 is reduced compared with the prior art arrangements, a most important advantage of this arrangement is the fact that the direction of the resultant stress in the new and improved arrangement is more nearly perpendicular to axis 72 of the winding, than in the prior art, which thus stresses the adjacent insulating members more in puncture and less in creep, than does the prior art arrangements, exemplified by the vector diagram shown in FIG. 3. Advantage is taken of the much higher strength of the insulating members in puncture than in creep, which substantially reduces the possibility of failure occurring at this area. Insulating clearances may be reduced between the second and third pancake coils, and from the pancake coils to the low voltage winding, or the present insulating clearances may be maintained with a higher factor of safety in the design. Further, when the winding must be upgraded to higher BIL ratings, it will not be necessary to increase the insulating clearances at this location by the factor that they would ordinarily have to be increased.

Since the "weakest point" stress-wise of a twin interleaved winding, due to stresses between the innermost turns of adjacent pancake coils, is between the second and third pancake coils, the remaining basic pairs of twin interleaved pancake coils may be constructed in the same manner as the first basic pair, comprising pancake coils 74 and 76. Thus, the reduction in stress, and the change in the direction of the resultant stress at this location, is obtained without a costly change in the overall winding. In fact, it only requires reversing the normal sequence of the third and fourth pancake coils, and making a finish-start connection between the second and third pancake coils, instead of a finish-finish connection.

While the invention has been described relative to one end of a stack of pancake coils, it will be understood that if the high voltage winding is of the type where both ends of the winding are connected to a high voltage line terminal, that the same change should be made at the other end of the winding.

In summary, there has been disclosed a new and improved high voltage winding for power transformers of the core-form type, which utilize the twin interleaved winding arrangement for increasing the through or series capacitance of the winding, to more uniformly distribute surge potentials across the winding. The disclosed structure reduces the voltage stress adjacent the inner turns of the second and third pancake coils, and changes the direction of the stress at this location, to more efficiently utilize the insulating materials disposed between the high voltage winding in the pancake coil, and between the pancake coils. In addition, the disclosed structure reduces the magnitude of oscillatory voltages produced in response to surge potentials, retaining the advantage of the structure disclosed in my copending application.

Since numerous changes may be made in the above described apparatus, and different embodiments of the inven-

tion may be made without departing from the spirit thereof, it is intended that all matter contained in the foregoing description or shown in the accompanying drawings shall be interpreted as illustrative, and not in a limiting sense.

I claim:

1. A winding for electrical inductive apparatus, comprising: at least first, second, third and fourth pancake coils disposed in spaced, side-by-side relation; each of said pancake coils having a plurality of turns of first and second conductors wound together to provide first and second radially interleaved coil sections, respectively each having inner and outer ends, with the innermost turn being in the first coil section and the next to the innermost turn being in the second coil section; means interconnecting the inner ends of the first coil sections, and the inner ends of the second coil coils; of said first and second pancake coils, means interconnecting the outer ends of the first and second coil sections of said first and second pancake coils respectively;

means interconnecting the outer ends of the first coil sections, and the outer ends of the second coil sections, of said third and fourth pancake coils;

means interconnecting the inner ends of the second and first coil sections of the third and fourth pancake coils, respectively, and

means interconnecting the outer and inner ends of the first coil sections of said second and third pancake coils, to provide a single series circuit through said first, second, third and fourth pancake coils.

2. The winding of claim 1 including a line terminal adapted for connection to a source of electrical potential, said line terminal being connected to the outer end of the second coil section of the first pancake coil.

3. The winding of claim 1 wherein the second and third pancake coils are wound in a circumferential direction which is opposite to the circumferential direction of said first and fourth pancake coils, to provide an additive magnetomotive force.
